UNITED STATES PATENT OFFICE.

ANTON C. SCHUERMANN, OF DECATUR, ILLINOIS, ASSIGNOR TO H. MUELLER MANUFACTURING COMPANY, OF DECATUR, ILLINOIS, A CORPORATION OF ILLINOIS.

COMPRESSION STOP AND WASTE.

No. 843,496.

Specification of Letters Patent.

Patented Feb. 5, 1907.

Application filed March 15, 1906. Serial No. 306,311.

To all whom it may concern:

Be it known that I, ANTON C. SCHUERMANN, a resident of Decatur, in the county of Macon and State of Illinois, have invented 5 a certain new and useful Compression Stop and Waste, of which the following is a specification.

The invention is applicable to stop and waste cocks or faucets to hydrants and to 10 other appliances that act on the stop and waste principle.

The principal object of the invention is to avoid opening the two valves of a compression stop and waste at the same time, thus 15 precluding the possibility of water or other fluid being forced through the waste by pressure on the fluid; and another object is to insure the operation of the invention as an ordinary stop and waste in case the spring 20 that prevents the opening of both valves at once should become broken.

The invention is exemplified in the structure hereinafter described, and it is defined in the appended claims.

25 In the drawings forming part of this specification, Figure 1 is a central section lengthwise of a stop and waste in which my invention is embodied, the main valve being shown open and the waste-valve closed. Fig. 2 is a cross-section on line z in Fig. 1. Fig. 3 is a central section lengthwise of the cock, showing both valves closed; and Fig. 4 is a similar section showing the waste-valve open and the main valve closed.

35 The body 1 of the cock has a valve-seat 2 and a cylindrical extension 3 in axial alignment with the valve-seat. A bonnet 4 is secured to extension 3 by means of a union-nut 5, and it has an internal shoulder 4^a, 40 against which the waste-valve collar bears when the waste-valve is wide open. A packing-nut 6 is screwed onto the upper end of bonnet 4, and packing 7 is interposed between the nut 6 and the bonnet. A valve- 45 stem 8 extends through cap 6, packing 7, bonnet 4, and it is screw-threaded on its lower end to enter the internally-screw-threaded valve-plunger 14. A handle 9 is secured to the upper end of the valve-stem, and a valve- 50 collar 10 is formed on the stem between its ends. A valve-seat ring 12 is provided with a flange that is held between the bonnet 4 and the body extension 3, and a valve-seat 12^a is formed on the upper surface of the

valve-seat ring. The valve-collar 10 has 55 a downward-presented annular recess, and a valve-ring 11 is held in the collar in position to close against seat 12^a.

The body extension 3 has a plurality of internal lengthwise grooves, preferably four, 60 as shown at 3^a in Fig. 2, and the valve-plunger has a less number of ribs 15, preferably two, which slide in grooves 3^a and prevent the plunger from turning. A valve-disk 16 is held in the lower end of plunger 14 by 65 means of a screw 17, a waste-pipe 19 penetrates the bonnet above valve-seat 12^a, and a spring 18 is interposed between collar 10 and the upper end of the inner surface of the bonnet.

70 As shown in Fig. 1, the valve 11 rests on the valve-seat 12^a and holds the stem from farther descent, while the screw-threads 13 are screwed into the internal threads 14^a of the valve-plunger sufficiently far to raise the 75 upper end of the plunger against the under side of ring 12. Under these conditions the ring 12 is clamped between the valve 10 and the plunger, and the waste-valve is held 80 securely closed, while the main valve is held positively and securely in an open position. When the main valve is open, the fluid passes through the cock in an obvious manner.

85 When it is desired to close the main valve, the valve-stem is turned in a direction to unscrew the stem from the plunger. The spring 18 holds the waste-valve seated. The ribs 15 move down grooves 3^a and hold the plunger from turning, and the plunger descends until the valve-disk 16 is in contact with seat 2, as shown in Fig. 3. To open the waste-valve, the rotation of the stem is continued in a direction to unscrew the stem from the plunger. The contact of the main 90 valve with its seat prevents farther descent of the plunger, and so the waste-valve is raised against the action of spring 18. When the waste-valve is raised until the collar 10 contacts with shoulder 4^a, the main valve is 95 held positively closed independent of the action of the spring, and the waste-valve is of course held positively opened. When the waste-valve is raised from its seat, a waste- 100 passage is established through the unobstructed grooves 3^a in extension 3, through valve-ring 12, and through pipe or outlet 19. In closing the waste-valve preparatory to 105

and a collar 17, which are firmly attached to the shaft by transverse pins or otherwise. Surrounding the extension 16 is an expanding spiral spring 18, which has its inner end abutting against the collar 17 and its forward end 19 preferably engaging an opening 20 in a sleeve or ring 21. The sleeve 21 in turn rests against the portion 12 of the fan. A fiber friction-disk 22 is preferably located between the outer face of the hub 12 and the friction thrust-disk 10, though this latter is not absolutely essential. It seems, however, to take part of the wear and to increase the frictional contact of the front end of the hub in respect to the coacting friction-disk 10.

In operation the engine is started as usual in any suitable manner. Usually a starting-crank, such as 23, is provided for that purpose, though other means of starting may be utilized. As stated, an explosive-engine starts suddenly, and the fan being frictionally held on its shaft by the means here shown and described the sudden shock to the gearing is relieved. Also explosive-engines when running are frequently suddenly speeded to a very high speed. In such event the shock to the fan-gearing is relieved for the moment by the friction arrangement; but the frictional drive will gradually take hold until the fan is running at the proper speed.

Attention is directed to the fact that the driving frictional surfaces are so arranged that the air-pressure upon the blades of the fan will cause a frictional thrust in addition to that caused by the expanding-spring 18. This tends to cause the frictional contact to be increased when required for high speed, but is of such extent as to permit the fan to slip when the engine is started or suddenly speeded.

The construction here shown and described is found to embody a principle of operation that is found exceedingly efficient and to permit the use of the desirable gear-driven fan without its recognized disadvantages, heretofore pointed out.

Having thus described our invention, what

we claim, and desire to secure by Letters Patent, is—

1. The combination with an explosive-engine, of a fan-shaft, gears positively connecting the engine with the fan-shaft, a fan loose on the fan-shaft, a friction-disk fast on the fan-shaft and coacting with the fan-hub for driving the fan, an expanding-spring having one end coacting with the opposite side of the hub from the said friction-disk, and the opposite end of the spring held by a shoulder on the fan-shaft, the parts coöperating as described. 50

2. The combination with an explosive-engine, of a fan-shaft, gears positively connecting the engine with the fan-shaft, the fan having an elongated hub loose on the shaft, a friction-disk fast on the shaft and coöperating with one side of the hub for driving the fan, and an expanding-spring coöperating with the opposite side of the hub for the purpose described. 60

3. The combination of a fan-shaft, means for driving it at different speeds, a fan loose on the shaft, friction devices between the fan and its shaft for driving it, the friction devices so located that the air resistance upon the blades of the fan causes the friction to increase or decrease according to the speed of the fan. 70

4. The combination of a fan-shaft, means for driving the shaft at different speeds, a fan loose upon the shaft, friction driving devices between the shaft and the fan, means forcing the friction devices together, the friction devices being so arranged that the air resistance to the blades of the fan will add to the frictional engagement of the friction driving devices when the speed of the fan is increased. 80

In testimony whereof we affix our signatures in presence of two witnesses.
